Primary Examiner — Ricky Pham(74) *Attorney, Agent, or Firm* — Swanson & Bratschun, L.L.C.(57) **CLAIM**

The ornamental design for a nutrient capsule for an electric vortex mixer, as shown and described.

DESCRIPTION

FIG. 1 is a perspective view of a nutrient capsule for an electric vortex mixer that embodies the present design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.
